[57] CLAIM

The ornamental design for a nebulizer cup, as shown.

DESCRIPTION

FIG. 1 is a side elevational view of one side of a nebulizer cup embodying the new design;

FIG. 2 is a front elevational view thereof;

FIG. 3 is a side elevational view of the other side thereof;

FIG. 4 is a rear elevational view thereof;

FIG. 5 is a top plan view thereof; and

FIG. 6 is a bottom plan view thereof.
